UNITED STATES PATENT OFFICE.

PETER C. SCHAEFER, HORACE D. HULSE, AND GEORGE M. LIVINGSTONE, OF DENVER,
COLORADO, ASSIGNEES TO SAID PETER C. SCHAEFER.

AUTO-PORCH BED.

1,347,412.

Specification of Letters Patent.

Patented July 20, 1920.

Application filed January 20, 1920. Serial No. 352,847.

To all whom it may concern:

Be it known that we, PETER C. SCHAEFER, HORACE D. HULSE, and GEORGE M. LIVINGSTONE, citizens of the United States, residing at Denver, in the county of Denver and State of Colorado, have invented certain new and useful Improvements in Auto-Porch Beds, of which the following is a specification, reference being had therein to the accompanying drawings.

This invention relates to an auto-porch bed.

The object of the invention is the construction of a portable couch or bed that can be quickly set up or taken down and closed into a comparatively small roll or package, for the efficient handling of the same, either in a home or during traveling in a motor vehicle.

Another object of the invention is the construction of a quickly demountable bed which includes side structures that are susceptible of being folded together in a small space and in a compact manner.

With these and other objects in view, our invention comprises certain combinations, arrangements and constructions as will be hereinafter specifically described, illustrated in the accompanying drawings, and more particularly pointed out in the accompanying claims.

In the drawings:

Figure 1 is a perspective view of an apparatus constructed in accordance with the present invention, while

Fig. 2 is a view in side elevation of the same.

Fig. 3 is a perspective view of the top structure, partly rolled, and showing the side structures in a folded position thereon.

Fig. 4 is a perspective view of the apparatus as it appears when rolled together and ready for storing away in a building or in a motor vehicle.

Fig. 5 is a view in side elevation of one of the side structures, partly shown in a folded position and indicating by dotted lines the line of movement of the parts when positioning same for supporting the top structure of the bed or apparatus.

Fig. 6 is a fragmentary end view of one of the side structures, while

Fig. 7 is a fragmentary front view of the same.

Fig. 8 is an enlarged side view of one of

the ends of one of the primary side rails, while

Fig. 9 is a sectional view, taken on line 9—9, Fig. 8.

Referring to the drawings by numerals, 1 is a fabric, such as heavy canvas ducking. This fabric is attached at one end to the bar 2, and the bar 2 is fastened to the angle iron end piece 3. The opposite end of the fabric 1 is provided with a plurality of straps 4, and rings 5 are carried by these straps, to which rings are attached the inner ends of helical springs 6; the outer ends of springs 6 are attached to the angle iron end piece 3^a.

Each end piece 3 and 3^a is provided on its outer face and near its ends with guide brackets 7 in which are positioned upright standards 8 when the apparatus is set or is in its operative position, Fig. 1.

The top structure of our bed, therefore, comprises the fabric 1, the angle iron end pieces 3 and 3^a, together with the means for connecting the fabric to the end pieces.

In constructing our apparatus or foldable bed, we use two similarly constructed side structures. Each side structure comprises a primary side rail 9, provided on its upper face and at its ends with substantially U-shaped brackets 10; pivotally mounted at their inner ends, at 11, within the brackets 10 are primary arms 12. These arms are adapted to fold over and rest upon the top of the primary side rail when the apparatus is in its closed position, as more clearly illustrated in Figs. 3 and 5. Each primary arm 12 is provided with an angularly disposed outer end 13, which end 13 fits in a horizontal bracket 14 fastened to the inner face of the horizontal portion of the end piece 3, or 3^a; each end piece has two of these brackets 14 near its ends, the same as there are two of the vertically-positioned brackets 7 attached to the outer face of the vertical portion of each end piece.

Each primary side rail is substantially U-shaped in cross section (Fig. 9) and pivoted upon rivets 15 (Figs. 8 and 9) are auxiliary arms 16; by means of the arms 16 being pivoted at their inner ends within the sides of the rails 9, these arms will fold down snug upon the primary rail, as indicated in Figs. 3 and 5. A jointed auxiliary rail 17 is attached at 18 to the inner sides of the auxiliary arms 16 for bracing and strengthening these arms; however, the cen-

tral portion of the auxiliary rail 17 will fold up and into the U-shaped body of the primary rail 9 when the parts are folded together as shown in Fig. 5.

5 Brackets 19 are secured to the top of the auxiliary arms 16 at their outer ends and the upright standards 8 are pivotally mounted on these brackets, at 20. Each standard 8 is substantially U-shaped in cross section and 10 fastened within the upper end of each standard is a spring catch 21 that is adapted to snap over the upper portion of an end piece to prevent the end piece from accidentally slipping over the top of the standards when 15 the bed is in its set or operative position, Fig. 1; these spring catches 21 constitute locking means carried by the standards for preventing the top structure of the bed from accidentally being displaced off the standards.

20 At each end of the apparatus is a jointed intermediate brace 22, the upper end of which is pivotally connected, at 23, to the standard 8 near its upper end, and the lower 25 end of the brace is connected, at 24 (Fig. 2), to the auxiliary arm near its middle. When the apparatus is in its set or open position, these intermediate braces further assist in holding the same in a secure position to support the weight upon the fabric 1. End 30 braces 23^a are provided, being pivotally connected, at 24^a, upon the end pieces, and each provided with a notch 25 near its lower end to hook over the stud 26 carried by the 35 standard 8 near its lower end.

40 To set up the apparatus, the side structures are taken from their resting position, Fig. 3, thence moved to a vertical position, Fig. 5, and the arms are swung outwardly, 45 as clearly indicated by dotted lines, causing the standards 8 to be positioned in a vertical plane, thence placing the upper end of the standards through the brackets 7 and at the same time running the angularly disposed ends 13 of the primary arms 12 into brackets 14, whereupon the spring catches 21 will snap over the top of the end pieces and then by straightening the jointed intermediate braces 22 and hooking the lower ends of the 50 braces 23^a over studs 26, the entire apparatus will be assembled and ready for use.

55 To knock down, or unset the apparatus, all that it is necessary to do is to force outward the spring catches 21, so that the end pieces may be lifted off the standards 8 and by a slight outward movement the arms 12 will be disengaged from the brackets 14, thus permitting the entire top structure to be removed and rolled, as shown in Figs. 3 60 and 4. Upon the removal of the top structure, then the two side structures can be folded together, as clearly shown in Figs. 3 and 4, thence placed upon the top structure, having all of the parts rolled together into 65 a single roll and then binding straps 27 may

be employed for fastening the entire apparatus in a compact solid roll and ready for storing or transportation, at the will of the operator.

70 While we have described the preferred embodiment of our invention, and have illustrated the same in the accompanying drawings, in the extensive manufacture of the apparatus, certain minor alterations or changes may appeal to one skilled in the art 75 to which this invention relates and we, therefore, reserve the right to make such alterations or changes as shall fairly fall within the scope of the appended claims.

80 What we claim is:

1. In an apparatus of the class described, the combination of a pair of side structures, each said structure comprising a rail, of primary and auxiliary arms pivotally connected to the ends of said rail, standards 85 pivotally connected to the auxiliary arms, intermediate braces connected to the standards and to the auxiliary arms, an auxiliary side rail connected to the auxiliary arms, and a top structure detachably supported 90 upon the standards and the primary arms.

2. In an apparatus of the class described, the combination of a pair of side structures, each side structure comprising a primary side rail U-shaped in cross section, U-shaped 95 brackets secured to the upper face of and at the ends of said side rail, primary arms pivotally mounted at their inner ends within said brackets, auxiliary arms pivotally secured at their inner ends with said side rail, 100 each primary arm provided with an outer angularly-disposed end, an auxiliary jointed rail pivotally connected at its ends to the inner faces of said auxiliary arms, brackets secured to the upper faces of and at the 105 outer ends of the auxiliary arms, standards U-shaped in cross section pivotally mounted at their lower ends upon said last-mentioned brackets, spring catches attached in the U-shaped body of the standards near their upper ends, intermediate jointed braces secured to the standards and to the auxiliary arms, a top structure including end pieces, brackets secured to the end pieces upon their outer and inner faces, said standards adapted to 110 be positioned in the brackets on the outer faces of the end pieces, said catches adapted to snap or hook over the top of the end pieces, and said angularly-disposed ends of the primary arms adapted to be positioned 115 in the brackets on the inner face of said end pieces.

3. In an apparatus of the class described, the combination of a pair of side structures, each side structure including a side rail, primary arms pivotally mounted upon the top of the side rail and adapted to be folded over against the same and also adapted to be folded outwardly for supporting the top structure, auxiliary arms pivotally connected 125 130

- to the under face of the side rail and adapted to be folded inwardly toward and against the rail and also adapted to be extended outwardly to a supporting position, standards 5 pivotally mounted upon the auxiliary arms and adapted to be positioned in a vertical plane for receiving the top structure, and a top structure supported upon the primary arms and the standards.
- 10 4. In an apparatus of the class described, the combination of side rails, primary arms pivotally mounted upon said side rails, auxiliary arms pivotally mounted upon said side rails, standards pivotally mounted upon 15 said auxiliary arms, a jointed brace positioned between and connected to each pair of auxiliary arms, an intermediate brace interposed between and connected to each contiguous auxiliary arm and standard, and 20 a top structure detachably supported upon the primary arms and the standards.
5. In an apparatus of the class described, the combination of a pair of side structures, each side structure including a side rail U-shaped in cross structure, a pair of brackets 25 secured to the upper face at the ends of said side rail, primary arms pivotally mounted at their inner ends within said brackets, aux-
- iliary arms pivotally mounted at their inner ends within the U-shaped side rail, said 30 primary and auxiliary arms provided with angularly-disposed outer ends, a bracket secured upon the angularly-disposed outer end of each auxiliary arm, a standard pivotally mounted with the last-mentioned bracket, a 35 top structure including angle iron end pieces, said angularly-disposed outer ends of the primary arms resting under a part of the end pieces and said standards bearing against the outer faces of the end pieces contiguous to and in front of the outer ends of 40 the primary arms.
6. In an apparatus of the class described, the combination of end structures including movably-mounted arms and movably-mounted standards, a top structure including ends positioned down between the outer ends of the arms and the inner faces of the standards, and means detachably fastening the ends of the top structure, arms and 50 standard against accidental displacement.
- In testimony whereof we hereunto affix our signatures.

PETER C. SCHAEFER.

HORACE D. HULSE.

GEORGE M. LIVINGSTONE.
